United States Patent

Des. 236,886
Patented Sept. 23, 1975

236,886

PALLET

Burton A. Johns, Santa Ana, Calif., assignor to Burton A. Johns, John M. Loechner, and John K. Griff, all of Santa Ana, and Gary J. Griff, Palos Verdes Estates, Calif., fractional part interest to each

Filed Oct. 9, 1973, Ser. No. 404,390

Term of patent 14 years

Int. Cl. D9—99

U.S. Cl. D12—53

FIG. 1.

FIG. 2.

FIG. 3.

FIG. 4

FIG. 1 is a top perspective view of the pallet showing my new design;

FIG. 2 is a side elevational view thereof showing the longer side of the legs;

FIG. 3 is a bottom perspective view thereof; and

FIG. 4 is a side elevational view thereof showing the shorter side of the legs.

I claim:

The ornamental design for a pallet, as shown.
